UNITED STATES PATENT OFFICE.

HARRY SOTH, OF MILWAUKEE, WISCONSIN.

TOY.

1,249,538.

Specification of Letters Patent. Patented Dec. 11, 1917.

Application filed May 7, 1917. Serial No. 166,852.

To all whom it may concern:

Be it known that I, HARRY SOTH, a citizen of the United States, and resident of Milwaukee, in the county of Milwaukee and 5 State of Wisconsin, have invented certain new and useful Improvements in Toys; and I do hereby declare that the following is a full, clear, and exact description thereof.

My invention relates to new and useful 10 improvements in toys and particularly to a toy of the type in which a drum or pulley is employed adapted to travel up a cord, the pulley being colored, as for instance, red, white, and blue, in such a manner as to give 15 a pleasing appearance to the eye when being manipulated.

The primary object of my invention is to provide a simple toy which will be highly 20 amusing to both young and old, which may 25 be used as a patriotic toy, or which may be used for the purpose of advertising.

A further object of my invention is the provision of a toy of the character described, which will be of extremely simple construction, and will therefore be manufactured at 25 an extremely low cost.

With the above and other objects in view, which will appear as the description proceeds, my invention resides in the novel construction, arrangement and combination of 30 parts substantially as herein described and more particularly defined by the appended claims, it of course being understood that such changes may be made in the precise 35 embodiment of the invention herein disclosed as will come within the scope of the claims.

In the accompanying drawings I have 40 illustrated one complete example of the physical embodiment of my invention constructed according to the best mode I have so far devised for the practical application of the principles of my invention.

Figure 1 is a side view in elevation of my 45 toy, and

Fig. 2 is a view in elevation looking in the direction indicated by arrows 2—2 in Fig. 1.

My invention comprises essentially an exteriorly screw threaded or grooved drum or 50 pulley 5 which has extending therein from side to side the three spaced apertures 6 and has extending centrally therethrough a metal or other bushing 7 forming the bearing for the pulley on the pivot 8 which has 55 extending laterally therefrom in opposite directions the arms 9 and 10 having their

ends inwardly bent as at 11 and 12 to be parallel with the pivot 8. The ends of the arms 11 and 12 are coiled as at 13 and 14 respectively, the openings of which coils are in 60 approximate alinement. Extending out from the coil 14 is the extension 16 adapted to receive a flag or suitable advertisement 17, and formed on the coil 13 is the hook 18 adapted to receive any desired attachment, 65 the extension 16 having its flag extending centrally over the drum.

Secured to the drum is the end 19 of a wire or cord 20 which is wound several times around the drum extending downwardly and through the opening formed in the coil 13, and also having its end 21 secured in the drum, is a lighter cord or wire 22 which is wound several times around the drum in a direction opposite to that of the 75 cord 20 and passes up through the opening formed in the coil 14.

The drum 5 is divided into an inner, intermediate and outer colored portions 23, 24, and 25 being blue, white, and a bright red 80 respectively, the colors making a pleasing display when the drum is caused to ascend or descend as it will be apparent.

Having thus described my invention in as clear and precise a manner as possible, I 85 will now endeavor to set forth its operation which is as follows:

The upper lighter cord may be secured to any suitable support or held in one hand, and the lower heavier cord is held in the 90 other hand and when stress is applied the drum will ascend up the lighter cord and when the stress is released it will descend. This being accomplished by the lighter cord sinking deeper into the groove than the 95 heavier cord thereby having less leverage than the heavier cord, and thus causing the drum, as aforesaid, to travel up the lighter cord as will be apparent to those skilled in the art to which an invention of this character appertains.

I claim:

1. A toy of the character described comprising an exteriorly screw threaded drum of the same diameter throughout, a pivot 105 therefor, a light and heavy cord oppositely wound on the drum, and guiding means carried by the pivot and engaging the cords.

2. A toy of the character described comprising a pivot member having arms laterally extending therefrom in opposite directions, said arm members having alined

openings in their outer ends, an exteriorly screw threaded drum mounted on the pivot and of the same diameter throughout, and means engaging the grooves of the drum and passing through the openings in the arms of the pivot member to cause said drum to ascend and descend substantially as described.

3. A toy of the character described comprising an exteriorly screw threaded drum of the same diameter throughout, a pivot therefor, oppositely extending arms formed on the pivot, a light and a heavy cord having their inner ends secured to the drum and wound therearound in opposite directions, the outer ends of the cords slidably engaging the end of the arms of said pivot, and a display flag carried by one of said arms.

4. A toy of the character described comprising a drum, a pivot for the drum, lateral arms formed on said pivot and extending in opposite directions, a light and a

heavy cord having their inner ends secured to the drum and partially wound therearound in opposite directions, the outer ends of the cords slidably engaging the ends of said lateral arms, and a display flag carried by one of said arms, said drum having a series of apertures therein and having its sides painted to represent the colors of an American flag substantially as described.

5. A device of the character described, comprising a drum, a pivot for the drum, a light cord wound on the drum, a heavy cord wound on the drum opposite to the light cord, guides for the cords and carried by said pivot, said drum being adapted to travel up the light cord when stress is applied to the cords, substantially as described.

In testimony that I claim the foregoing I have hereunto set my hand at Milwaukee, in the county of Milwaukee and State of Wisconsin.

HARRY SOTH.
